15 Claims.

(Cl. 8—159)

This invention relates to the washing and cleaning of fabrics and articles and more particularly to power driven washing and cleaning machines.

5 The invention provides a washing and cleaning machine of extremely simple construction which provides all essential operations to effect a rapid and thorough cleaning or washing of the articles. These operations include circulation of the articles in the washing fluid, scrubbing and shaking of the articles, agitating and flexing of the fabric of the articles and rapidly pulsating the fluid through the fabric.

10 The machine of the present invention includes a rapidly reciprocating washing element submerged in the washing fluid, provided with one or more circumferential projections or disks serving as scrubbing surfaces and as means providing a unidirectional flow or circulatory motion of the fluid whereby the articles being cleaned are successively and repeatedly drawn into a scrubbing zone adjacent the washing element wherein they are scrubbed and vigorously shaken. Additionally, the motion of the washing element produces sufficiently vigorous pulsations which spread 15 throughout the body of the fluid and serve to loosen and remove dirt by rapidly flexing and agitating the articles and pulsating the fluid through the fabric. The washing element also 20 functions to untangle any fabric or article which may have become tangled with another or others during the washing action.

25 The intensity and rapidity of the washing action may be readily varied by a simple adjustment of the stroke of the washing element to produce as gentle or as vigorous a washing action as may be desired to suit the particular type of fabric undergoing treatment. The structure of the washing element permits the use of an elastic 30 material which will preclude injury to fabrics even with the most vigorous washing action. The speed and direction of the circulation of the fluid and the articles being treated may be altered by 35 variations in the form and size of the washing element.

40 The invention in its several aspects will be understood from the following description considered in connection with the accompanying drawing forming a part thereof, and in which:

45 Fig. 1 is a more or less diagrammatic view in vertical section of a washing machine embodying the invention;

50 Fig. 2 is a sectional view of the operating mechanism for the washing element, taken substan-

tially on line 2—2 of Fig. 1, and on an enlarged scale;

5 Fig. 3 is a sectional view, on an enlarged scale, taken on line 3—3 of Fig. 2;

Fig. 4 is a vertical sectional view, on an enlarged scale, of the washing element and the parts immediately associated therewith;

Fig. 5 is a vertical sectional view of another form of washing element; and

Fig. 6 is a vertical sectional view of a further 10 form of washing element.

Like characters of reference refer to the same or similar parts throughout the several views.

Referring to the drawing, particularly to the 15 machine illustrated in Figs. 1 to 4 inclusive, reference character 10 designates the tub of the machine which is preferably cylindrical in form, with a closed bottom 11 and an opening 12 at the top which may be closed by a hinged cover 13. The tub 10 is secured to a supporting pedestal 14 which also serves to support the operating mechanism for the washing element.

20 The washing element 15 is rapidly reciprocated with relatively short strokes in the treating fluid contained in the tub, and includes one or more 25 scrubbing surfaces which also produce circulatory motion of the washing fluid and pulsations in the fluid which are sufficiently vigorous to flex and agitate flexible articles being treated and to cause the fluid to be forced through the fabric of 30 the articles. In the form shown in Figs. 1 to 4, the washing element 15 is provided with four spaced projections or disks 16, 17, 18 and 19 respectively. In this instance, the disks are 35 constructed and arranged so as to cause the treating fluid and the articles being treated, to circulate in general as indicated by the flow lines in Fig. 1, that is, toward the center of the tub at the lower end of the washing element, upwardly at the center and along the element through the scrubbing 40 zone, then radially outwardly from the upper end or portion of the element and downwardly at the wall or the peripheral portions of the tub. Although the washing element may be constructed of rigid materials such as metal, hard rubber, 45 Bakelite, etc., I prefer using elastic and flexible material such as live rubber, or suitable rubber composition reinforced with fabric where necessary. Greater circulation of the fluid and more gentle treatment of the articles is thus obtained.

50 More specifically, the disks 16 and 17 of the washing element may be flexible rubber cups. These cups are disposed so as to be concave upwardly, as shown in Figs. 1 and 4, and as they are reciprocated, the bottom of the cups flex and the

walls, particularly the upper edge portions, expand and contract varying the angle of inclination of the upper edge portions with respect to the axis of reciprocation, whereby the effective fluid propelling area is increased or decreased, producing a pumping action which sucks the fluid and the articles at the bottom of the tub radially inwardly toward the washing element and into the scrubbing zone which may be considered as the space immediately surrounding the washing element. Disk 18 should also be flexible but it should not possess the degree of concavity of cups 16 and 17. Instead it should have an upwardly inclined flange on the order of that shown in Fig. 4, so arranged that it functions to take hold of the articles brought into the scrubbing zone by the cups 16 and 17 and to feed them upwardly in a series of relatively fast jerks toward the disks above. Disk 18 should be semi-flexible, that is, more rigid than the lower disks and is constructed and arranged to slap or pound the articles moving upwardly in the scrubbing zone and to push them and the treating fluid radially outwardly toward the wall of the tub in the upper portion of the fluid. This disk is curved outwardly and upwardly as shown in Fig. 4, with a concave lower surface, and is positioned to operate at the surface of the body of washing fluid. During operation, it projects the upper layer of the fluid and articles therein, outwardly toward the wall of the tub. Upon reaching or nearing the wall of the tub, the fluid and the articles will be forced to flow downwardly toward the bottom of the tub due to the action of the bottom disks 16 and 17 as previously described.

The disks on the washing element should be spaced apart a distance sufficient to allow each disk to fully perform its intended function. Although two pumping disks 16 and 17 are shown, a single disk of this character may be used where less vigorous circulation is desired.

The carrying and operating mechanism for the washing element 15 illustrated in Figs. 1 and 4, includes a sleeve 20 upon which the disks 16 to 18 are mounted and a shaft 21 arranged and supported to be rapidly reciprocated. Shaft 21 extends through the bottom 11 of the tub through a packing gland 22 carried by a flanged cylindrical member 23, the upper end of which extends through an aperture in the bottom 11 of the tub and is secured to the tub bottom by a retaining ring 24 which is threaded on the member 23 and forces the tub bottom against an annular rubber cushion 25 to thereby prevent leakage of the washing fluid. Space 26 in member 25, provides an oil and water collecting chamber. A drain tube may be connected to this chamber through which accumulated oil and water may be emptied. An inverted cup-shaped member 27 is threaded to the upper end of the member 23 and supports a stationary supporting tube 28 at its lower end. This tube is vertically disposed concentrically with the shaft 21 and extends upwardly in the tub to a point preferably above the level of the washing fluid therein. The outer sleeve 20 is secured at its upper end to the upper end portion of the shaft 21 by any suitable means such, for example, as illustrated in Fig. 4. A supporting collar 29 is secured to the lower end of the sleeve 20 and serves to support the lowermost cup 16. A retaining ring 30 is threaded on the upper end of the outer sleeve and is turned down tightly against the uppermost disk 18. The disks 16 to 18 inclusive may be integral or one or more may

be separate from one or more of the others. The hubs of these disks may be of sufficient axial length to provide the desired spacing between their outer edges, or suitable other spacing means may be employed, if desired.

In the form of the invention illustrated, the machine is operated by an electric motor 31 through suitable mechanism for imparting to the washing element the necessary or desired rapid reciprocating motion. As shown, mechanism is provided for this purpose which is capable of adjustment so that the stroke of the washing element may be varied from zero to the maximum stroke for the mechanism. This mechanism includes an eccentric 32 fixed to the motor shaft 33 and an eccentric strap 34, having an arm 35 to the end of which is pivoted a rod 36 which functions as a lever, as will presently appear. Obviously, a crank may be substituted for the eccentric and strap, if desired. The other end of rod 36 is pivoted to one end 37 of a forked lever 38 pivoted intermediate its ends at fixed point 39 to spaced supporting members 40. The end 41 of lever 38 is connected to a block 42 through links 43. Block 42 is mounted on the reciprocating shaft 21 and may be fixed in suitable position thereon by a set screw 44 or other means. Slidably mounted on rod 36 is a sleeve 45 having spaced ears 46 which are pivotally connected to spaced lugs 47 mounted on a carriage 48. During operation of the device, rod 36 reciprocates within the sleeve 45. In the form shown, this carriage is threadedly mounted on an adjusting screw 49 which is supported on the supporting member 14 of the machine with one end extending outwardly beyond the member 14 and upon which is mounted a hand wheel 50 for operating the screw to adjust the position of the carriage 48 thereupon. The ears 46 and the lugs 47 on the sleeve 45 and carriage 48 respectively, are spaced apart a distance sufficient to permit the pivot pins 51 connecting them together, to receive the pivotally connected lugs of rod 36 and lever 38 so that the pins 51 may be brought into axial alignment with pin 52 connecting the rod 36 and lever 38. With this arrangement it will be perceived that with pivot 38 functioning as a fixed fulcrum for lever 38, operation of hand wheel 50 will move carriage 48 and sleeve 45 on rod 36 so that the pins 51 will function as a fulcrum for rod 36. This fulcrum may be moved to any position intermediate the position wherein it is in alignment with pin 52 and the opposite extreme position for the mechanism. Thus rod 36 will function as a lever and the motion imparted through the rod to lever 38 will depend upon the position of the carriage and the fulcrum. In consequence, by adjustment of hand wheel 50, the stroke of the reciprocating rod 21 which operates the washing element 15, may be gradually varied from zero to maximum for the device. With this arrangement, the intensity and rapidity of the washing action may be readily varied to produce as gentle or as vigorous a washing action as may be required for the particular fabrics or articles undergoing treatment so that the machine is readily adaptable to the washing of all types and kinds of fabrics from the most delicate and frail to the heaviest and most durable.

Forms of washing elements other than that disclosed in Figs. 1 and 4 may be employed, if desired, including washing elements with but a single disk. Other forms which have been found suitable for the purpose include those disclosed

in Figs. 5 and 6. However, it should be understood that the invention is not limited to the particular forms of washing elements herein disclosed, but that other forms and arrangements may be employed without departing from the principles of the invention.

In Fig. 5 the washing element consists of two spaced rubber cups 53 and 54 mounted on a reciprocating rod 21. The cups are mounted with their concave sides disposed downwardly which will cause the treating fluid and the articles being treated, to circulate downwardly in the scrubbing zone which is adjacent the washing elements, rather than upwardly in said zone as in the case of the washing element disclosed in Figs. 1 and 4. However, these cups may be inverted in position on the rod 21 to provide circulation through the scrubbing zone in an upward direction, if desired. As shown, the cups 53 and 54 have thickened peripheral edges but the cross-sectional configuration of these edges may be varied as desired. For instance, these edges may be wedge-shaped or tapered in cross-section to provide relatively thin peripheral edges which will give them greater elasticity. As shown, the upper cup 53 is somewhat smaller in overall diameter than the lower cup 54. The relative proportions of these cups may be varied so that both cups are of the same diameter or the lower cup is of smaller diameter than the upper cup.

In Fig. 6, the washing element has four disks 55, 56, 57 and 58 which are disposed on a reciprocating rod 21. These disks are in general similar to disk 18. Disk 55 being of greatest diameter has the greatest flexibility and during operation, the center of the disk reciprocates with shaft 21 and the outer peripheral portion moves considerably less, thereby producing pumping action toward the axis of the disk similar to the action of cup 16. The other disks 56, 57 and 58, being progressively smaller in diameter, possess progressively less flexibility, with the uppermost disk being fairly rigid. Thus, this arrangement functions in a manner similar to the washing element shown in Figs. 1 and 4.

Actual tests have indicated that very satisfactory results are obtained with a machine constructed and arranged as disclosed in Figs. 1 to 4 inclusive, with the washing element arranged as shown in these figures. With about 18 gallons of warm water and 4 ounces of soap in the tub and 12 pounds of soiled, dry clothes, and with the washing element reciprocating at the rate of 600 strokes per minute with a 1½ inch stroke, a perfect wash was obtained in 20 minutes of operation of the machine. The dimensions of the disks of the washing element in this instance were as follows: the lower cups 16 and 17 had outside diameters of 6 inches, and were 1½ inches in depth, disk 18 had an outside diameter of 7 inches and top disk 19 had an outside diameter of 5 inches. The cups were spaced about 2½ inches apart on the sleeve supporting them. During the operation of the machine, the water and the clothes continuously circulated in the tub in the direction indicated by the direction lines in Fig. 1 of the drawing and in the manner previously described in connection with Fig. 1.

Excellent results were obtained in a small washing machine utilizing a washing element arranged as shown in Fig. 5. 3½ gallons of soapy water and 2 pounds of soiled, dry clothes were used, the bottom cup was 4 inches in diameter and the top cup 3¾ inches in diameter, and the washing element was reciprocated with a ¾

inch stroke at 1,150 strokes per minute. Satisfactory washing action was obtained with the washing element operating at speeds from 675 to 1,150 strokes per minute with strokes between ¾ and ½ of an inch.

Although the washing element is disclosed herein as being centrally or axially disposed in the tub, it will be understood that other positions of the washing element in the tub will produce satisfactory results. The washing element may be placed at any suitable off-center position and may even be disposed closely adjacent the wall of the tub, if desired. Additionally, the washing element may be actuated from the top of the tub rather than from the bottom as illustrated.

With the machine arranged as disclosed in Fig. 1, the water level may be at different levels for different loads of articles to be treated. With small quantities of clothes or articles, for example less than 6 pounds, the water level may be at the level of the outer peripheral portions of the disk 18, in which event only the three lower disks will be submerged and only these three will function to produce washing action. With larger volumes of clothes, for example 6 to 12 pounds, the water level should be at the level of the outer peripheral portion of disk 19 as shown in Fig. 1, so that all four of the disks of the washing element will be operative to produce washing action. The uppermost disk will strike or slap the water and send it in a continuous spray which falls around the walls of the tub and tends to submerge the clothes by pushing them toward the bottom.

The washing elements constructed and operated as previously described produce a pulsating unidirectional flow of fluid. This character of flow is due to the fact that the disks of the washing element constitute fluid propelling projections, the upper and lower surfaces of which encounter different degrees of resistance to their passage through the fluid. With an element constructed and arranged as illustrated in Figs. 1 and 4, the disks encounter less resistance on their downward movement than on their upward movement, which is due primarily to their shape, specifically their upwardly inclined circumferential surfaces. This action is present whether the disks are of rigid material and construction or of flexible material or construction. When, however, the disks are of flexible or elastic material or construction, the effective diameters alternately decrease and increase during operation on their downward and upward strokes respectively whereby their fluid propelling action as previously described is further amplified. This pulsating unidirectional flow of the fluid carries the articles into proximity of the washing element which engages the articles singly and pulls them individually in a series of short, fast jerks past the scrubbing edges which shake, flex and briskly rub the fabrics and propel them upwardly and outwardly, after which they are carried by the currents of fluid to the bottom of the tub to begin a new cycle. Throughout the process of washing, the fluid continuously pulsates back and forth through the meshes of the fabric thereby loosening the dirt preparatory to its removal in the scrubbing zone. Whereas a steady pull would not loosen an article entangled in a mass, a series of fast, short jerks such as produced by the machine of my invention, readily does so.

Variations in the number of strokes per minute may be readily accomplished by any suitable means, such as a belt drive.

Inasmuch as the rate and direction of circu-

lation of the fluid, the intensity of the washing action, and other factors depend upon the shape, size, number and relative position and inclination of the surfaces of the disks as well as upon the operating speed of the washing element, it will be readily perceived that any or all of these factors may be modified as desired to meet any particular requirements.

In the embodiment of the invention herein disclosed, the washing element performs both the washing and fluid propelling functions. However, if desired, separate fluid circulatory means of suitable character, such as a pump, propeller, or the like, may be employed, in which event the washing element will perform only the washing function.

Due to the unique character of the circulatory motion obtained in the machine of my invention, the shape of the tub is immaterial, and rounded corners or inclined walls or the like are unnecessary, because during operation, the clothes or other articles discharged upwardly and outwardly upon the surface of the fluid impose their weight upon the other articles disposed at the outer peripheral portions of the tub and force these other articles downwardly and into the sphere of influence of the lower disk or disks of the washing element. This action is further assisted by the continuous outwardly directed spray sent out by the upper disk of the washing element which falls at the outer portions of the tub and upon the articles there disposed, thus submerging them, as previously described.

Whereas the direction of fluid circulation previously described is preferred, circulatory motion in the reverse direction may be utilized merely by inverting the surfaces of the disks of the washing element.

In the embodiment of the invention herein disclosed, the washing element is operated in a substantially cylindrical tub, but the washing element may be shaped to suit any other shape of tub, such as rectangular, in which case the washing element may consist of rigid or elastic strips of a configuration to conform to the shape of the tub to produce uniform circulation of fluid throughout the tub. For example, a long, rectangular tub may be used with a washing element positioned longitudinally in the latter and consisting of elongated strips supported by a vertically disposed plate which is vertically reciprocated rapidly with short strokes.

The mechanism herein disclosed for varying the stroke of the washing element may be applied to many other uses, such as variable stroke pumps, hammering and riveting machines, and any other devices employing vibratory or reciprocatory motion.

It will be obvious that changes may be made in the form, location, relative arrangement and the materials of the several parts of the machine disclosed, and that variations in the steps of the method or their sequence may be made without departing from the principles of the invention. Accordingly no intention is entertained to limit the invention except by the scope of the appended claims.

What is claimed is:

1. A fluid treating element for a fluid treating machine adapted to be operatively disposed in a tub of the machine, comprising a supporting member and a plurality of spaced, concavo-convex annular flanges of elastic material on said member, at least one of said flanges having greater elasticity than another.

2. A fluid treating element for a fluid treating

machine adapted to be operatively disposed in a tub of the machine, comprising a supporting member and a plurality of spaced, concavo-convex annular flanges of elastic material on said member, the flange at one end of the supporting member having greater elasticity than another flange.

3. A fluid treating element for a fluid treating machine adapted to be operatively disposed in a tub of the machine, comprising a supporting member and a plurality of spaced, concavo-convex annular flanges of elastic material on said member, the flange at one end of the supporting member having greater rigidity than another flange.

4. A fluid treating element for a fluid treating machine adapted to be operatively disposed in a tub of the machine, comprising a supporting member and a plurality of spaced, concavo-convex annular flanges of elastic material on said member, the flange at one end of the supporting member having greater elasticity than the flange at the other end thereof and the intermediate flanges having an elasticity substantially no greater than the endmost flange of greater elasticity.

5. A fluid treating element for a fluid treating machine adapted to be operatively disposed in a tub of the machine, comprising a supporting member and a plurality of spaced, concavo-convex annular flanges of elastic material on said member, at least one of the flanges having a greater degree of concavo-convexity than another flange.

6. A fluid treating element for a fluid treating machine adapted to be operatively disposed in a tub of the machine, comprising a supporting member and a plurality of spaced, concavo-convex annular flanges of elastic material on said member, one or more of said flanges having a diameter different from the diameter of another flange.

7. The method of treating articles with fluid in a tub or the like which comprises subjecting the fluid in a zone constituting a minor portion of its total volume, to repeated, intermittent, rectilinearly and rapidly applied impulses greater in one direction than in the opposite direction, the rapidity of said impulses being sufficiently great to cause the fluid and articles to flow unidirectionally through said zone in a series of radial circulatory paths, and subjecting the articles while passing through said zone to a rapid reciprocatory scrubbing action.

8. The method of treating articles with fluid in a tub or the like which comprises subjecting the fluid in a zone constituting a minor portion of its total volume, to repeated, intermittent, rectilinearly and rapidly applied impulses greater in one direction than in the opposite direction, the rapidity of said impulses being sufficiently great to cause the fluid and articles to flow unidirectionally through said zone in a series of radial circulatory paths, subjecting the articles while passing through said zone to a rapid reciprocatory scrubbing action, and causing the fluid to rapidly pulsate through the articles as they circulate in the fluid.

9. The method of treating articles with fluid in a tub or the like which comprises subjecting the fluid in a zone constituting a minor portion of its total volume, to repeated, intermittent, rectilinearly and rapidly applied impulses greater in one direction than in the opposite direction, the rapidity of said impulses being sufficiently great

- to cause the fluid and articles to flow unidirectionally through said zone in a series of radial circulatory paths, subjecting the articles while passing through said zone to a rapid reciprocatory scrubbing action, causing the fluid to rapidly pulsate through the articles as they circulate in the fluid, and subjecting the articles as they circulate in the fluid to vigorous flexing and shaking.
10. 10. The method of treating articles with fluid in a tub or the like which comprises subjecting the fluid in a zone constituting a minor portion of its total volume, to repeated, intermittent, rectilinearly and rapidly applied impulses greater in one direction than in the opposite direction, the rapidity of said impulses being sufficiently great to cause the fluid and articles to flow unidirectionally through said zone in a series of radial circulatory paths, subjecting the articles while passing through said zone to a rapid reciprocatory scrubbing action, and causing the articles during circulation to be engaged successively and individually and by a series of short, fast jerks to be separated from the remainder of the articles, thereby untangling them from the other articles.
11. Apparatus for treating articles with fluid comprising a tub, a rectilinearly reciprocable fluid propelling element in the tub spaced from the wall thereof to allow free circulation of the articles between the element and the tub wall and having a peripheral portion normally movable with respect to the element in response to the fluid pressure thereon substantially within the limits of a quadrant the major portion of which lies on one side of a plane passing transversely through the axis of reciprocation of the element whereby a greater fluid propelling force is produced in one direction than in the opposite direction, and short stroke, high speed power driven means associated with the tub and connected to the element to reciprocate the element rectilinearly and to operate said peripheral portion to impart to the fluid in the zone surrounding the element, a series of short, rapid, intermittent, unidirectional impulses whereby unidirectional flow of the fluid is produced in the tub about the element in a series of circulatory paths lying substantially in planes disposed radially with respect to the axis of reciprocation.
12. Apparatus for treating articles with fluid comprising a tub, a fluid propelling element in the tub spaced from the wall thereof to allow free circulation of the articles between the element and the tub wall and having an outwardly flaring bendable elastic peripheral portion bending in response to the fluid pressure thereon to increase the flare when moved in one direction and to decrease the flare when moved in the opposite direction, and short stroke, high speed power driven means associated with the tub and connected to the element to reciprocate the element rectilinearly and to operate said peripheral portion to impart to the fluid in the zone surrounding the element, a series of short, rapid, intermittent, unidirectional impulses whereby unidirectional flow of the fluid is produced in the tub about the element in a series of circulatory paths lying substantially in planes disposed radially with respect to the axis of reciprocation.
13. Apparatus for treating articles with fluid comprising a tub, a rectilinearly reciprocable fluid propelling element in the tub spaced from the wall thereof to allow free circulation of the articles
- between the element and the tub wall and having peripheral means inclined to the axis of reciprocation of the element and movable in response to the fluid pressure thereon to vary the angle of inclination thereof to the axis of reciprocation of the element, the movement of said peripheral means being between positions of different inclination thereby providing greater effective fluid propelling area upon movement of the element in one direction than is provided upon movement of the element in the opposite direction, and short stroke, high speed power driven means associated with the tub and connected to the element to reciprocate the element rectilinearly and to operate said peripheral portion to impart to the fluid in the zone surrounding the element, a series of short, rapid, intermittent, unidirectional impulses whereby unidirectional flow of the fluid is produced in the tub about the element in a series of circulatory paths lying substantially in planes disposed radially with respect to the axis of reciprocation.
14. Apparatus for treating articles with fluid comprising a tub, a rectilinearly reciprocable fluid propelling element in the tub spaced from the wall thereof to allow free circulation of the articles between the element and the tub wall and having peripheral means inclined to the axis of reciprocation of the element and movable in response to the fluid pressure thereon to vary the angle of inclination thereof to the axis of reciprocation of the element within the limits of a quadrant the major portion of which lies on one side of a plane passing transversely through the axis of reciprocation of the element whereby the effective fluid propelling area is increased upon movement of the element in one direction and is decreased upon movement of the element in the opposite direction, and short stroke, high speed power driven means associated with the tub and connected to the element to reciprocate the element rectilinearly at a speed sufficiently great to cause the fluid pressure acting thereon to vary the angle of inclination of said movable peripheral means to impart to the fluid in the zone surrounding the element, a series of short, rapid, intermittent, unidirectional impulses whereby unidirectional flow of the fluid is produced in the tub about the element in a series of circulatory paths lying substantially in planes disposed radially with respect to the axis of reciprocation.
15. Apparatus for treating articles with fluid comprising a tub, a fluid propelling element in the tub spaced from the wall thereof to allow free circulation of the articles between the element and the tub wall, and having an outwardly flaring, stretchable, resilient, peripheral portion with a free edge, said portion bending in response to the fluid pressure thereon to increase the flare when moved in one direction and to decrease the flare when moved in the opposite direction, and short stroke, high speed power driven means associated with the tub and connected to the element to reciprocate the element rectilinearly and to operate said peripheral portion to impart to the fluid in the zone surrounding the element, a series of short, rapid, intermittent, unidirectional impulses whereby unidirectional flow of the fluid is produced in the tub about the element in a series of circulatory paths lying substantially in planes disposed radially with respect to the axis of reciprocation.

GEORGE KUHN.
